J. KOVACH

VENTILATING FAN

Filed Nov. 13, 1922

INVENTOR
John Kovach

BY

Marvin E. Gandy
ATTORNEY

UNITED STATES PATENT OFFICE.

JOHN KOVACH, OF TAMAROA, ILLINOIS.

VENTILATING FAN.

Application filed November 13, 1922. Serial No. 600,533.

To all whom it may concern:

Be it known that I, JOHN KOVACH, a citizen of Austria, residing at Tamara, in the county of Perry and State of Illinois, have 5 invented certain new and useful Improvements in Ventilating Fans, of which the following is a specification.

This invention relates to improvements in ventilating fans and means for operation 10 thereof, having as its main object to provide means for actuating one or more fans within a building by the force of air currents outside and above the building without the expenditure of energy as produced by engines, 15 motors and the like whereby expense is incurred.

This and like other aims, objects and purposes, as will become obvious as the description proceeds, are attained by the novel construction, combination and arrangement of 20 parts hereafter described and shown in the accompanying drawing constituting part of this disclosure, and in which:—

Figure 1 is a partial side elevation, partial 25 sectional view of an embodiment of the invention shown in operative position.

Figure 2 is a similar view of the same, looking from a plane at a right angle to Figure 1.

Figure 3 is a fragmentary sectional view 30 taken on line 3—3 of Figure 1.

Referring to the drawing, the numeral 10 designates in general the wall of a building having a roof 11 and ceiling 12, these elements being conventionally represented and constituting no part of the invention.

Mounted on the ceiling beams 12 is a flanged cylindrical casing 14 and in register thereabove is a similar cylindrical casing 40 15 set in the elements of the roof 11.

The interiors of both casings 14 and 15 are shaped to provide races or annular seats, respectively 16 and 17, for balls 18 and 19 on which rest discs 20 and 21.

45 Fixed in these discs is a shaft 22 having attached at its upper end a rectangular frame 23 in which is mounted a longitudinal spindle 24 at a right angle to the shaft 22 and carrying a fan 25 at one end and a vane 50 or rudder 26 at the other.

Mounted centrally on the spindle 24 is a

pulley 21 over which is trained a belt 28, the same extending down through suitable openings 29 in the discs 20 and 21 to engage another pulley 30.

55 Fixed on the lower end of the shaft 22 is a plate bar 31 below the ceiling 12 and secured to the bar is another frame 32 in which is rotatably mounted a spindle 33, carrying the pulley 30 and having fixed on 60 its extending ends, spur gears 34 and 35 respectively.

A yoke-shaped bracket 36 extends from one side of the frame 32 and in its outer end is engaged a vertical shaft 37, its upper end 65 being journaled in the bar 31, and its lower end engaging the hub of a fan 38.

Between the forked base elements of the bracket 36 is a stud 39 on which rotates a spur pinion 40 meshing with the teeth of the 70 gear 35.

Said pinion 40 has formed with it a miter pinion 41, meshing with a mating gear 42 fixed on the shaft 37, thereby conveying rotary motion to the fan 38 when the fan 25 75 is propelled by the wind, the fan 38 being positioned to direct an air current downwardly as shown.

Another fan 43 is carried on the end of a horizontal spindle 44 journaled in the opposite side of the frame 32 and driven by a spur pinion 45 engaging the spur gear 34, so that air currents are delivered simultaneously in different directions when the device is operating.

85 From the foregoing it will be seen that a simple, cheap and effective apparatus has been disclosed for producing air currents at no expense within a building whenever sufficient breeze is moving to produce motion in 90 the fan 25 and that the device is self adjusting to receive the best effect of the wind at all the times.

Having thus described my invention and set forth the manner of its construction, application and use, what I claim as new and desire to secure by Letters Patent, is:—

A ventilating apparatus comprising a pair of vertically aligned casings, thrust bearings carried by said casings, a shaft 100 supported thereby, frames attached to the ends of said shaft, one of said frames being

above the roof of a supporting building, and the other in a compartment below, a fan driven by the wind, said fan being housed in the upper of said frames, said casings and 5 bearings constituting means for rotating said frames and shaft when actuated by the wind, whereby said fan is adjusted to receive

the full force of the wind, a plurality of fans carried by the lower of said frames, and means for transmitting motion from 10 the first named fan to the other fans.

In witness whereof I have affixed my signature.

JOHN KOVACH.
